Henry Hood

By W. W. Williamson
Atty.

UNITED STATES PATENT OFFICE.

HENRY HOOD, OF PHILADELPHIA, PENNSYLVANIA.

SCREW-DRIVER.

1,244,981.

Specification of Letters Patent. Patented Oct. 30, 1917.

Application filed March 24, 1917. Serial No. 157,227.

To all whom it may concern:

Be it known that I, HENRY Hood, a citizen of the United States, residing at Philadelphia, in the county of Philadelphia and State 5 of Pennsylvania, have invented new and useful Improvements in Screw-Drivers, of which the following is a specification.

My invention relates to new and useful improvements in screw drivers, and has for 10 its object to provide an exceedingly simple and effective device of this character, in which the shank of the blade passes entirely through the handle, thereby making a more rigid tool, giving a more even balance to the 15 same, and reducing to a minimum the likelihood of the handle become loose on the blade or the shank thereof.

A further object of the invention is to provide a ferrule at each end of the handle for 20 rigidly securing said handle to the blade shank.

Another object of the invention is to provide a tool handle through which the tool shank passes, said handle being secured at 25 each end to the shank in a unique manner, without rivets passing through the handle, so that should said handle split from any cause whatsoever, it will be practically impossible to separate the handle from the tool shank.

With these ends in view, this invention 30 consists in the details of construction and combination of elements hereinafter set forth and then specifically designated by the claim.

In order that those skilled in the art to 35 which this invention appertains, may understand how to make and use the same, I will describe its construction in detail, referring by numerals to the accompanying drawings forming a part of this application, in 40 which—

Figure 1, is a side elevation of a screw driver in accordance with my improvement.

Fig. 2, is a longitudinal sectional view thereof.

Fig. 3, is an end view of the outer ferrule.

Fig. 4, is a section at the line 4—4 of Fig. 3.

Fig. 5, is a similar view of the inner ferrule.

In carrying out my invention as here embodied, 2 represents a tool blade provided with a shank 3 on which is mounted the handle 4 of wood or other suitable material hav-

ing a central bore 5 running entirely therethrough for the insertion of the shank 3. 55 The ends of the handle 4 are so formed as to produce frusto-conical extensions 6, the bases or larger portions of which are slightly smaller than the outer circumference of the handle to form shoulders 7. On the inner 60 end of the handle is mounted an inner ferrule 8 having a bore 9 which begins to flare outward and upward from a point intermediate the ends of the ferrule to produce a frusto-conical chamber 10, and the inner 65 walls of the ferrule in the region of the frusto-conical chamber are serrated as at 11. These serrations, when the ferrule is driven on the inner end of the handle, embed themselves in the frusto-conical extension 6 at the 70 inner end of the handle, and prevent the ferrule and handle rotating independent of each other, and this ferrule is rigidly fastened to the shank of the tool blade by a rivet 12 which passes entirely through the ferrule 75 and shank.

On the outer end of the handle is mounted an outer ferrule 13 having a central bore 14, which flares outward from a point intermediate its ends to produce a frusto-conical chamber 15, the walls of which are serrated as at 16 and these serrations are adapted to embed themselves in the frusto-conical extension 6 at the outer end of the handle when the outer ferrule is driven home, and 80 when properly positioned, the end of the shank is headed as at 17. When the ferrules are placed upon the handle, the inner edges engage the shoulders 7 on the handle and properly position the ferrules relative to the 85 handle.

The rivet 12 and the heading of the shank 17 securely fasten the ferrules to the shank, and said ferrules having their serrations embedded in portions of the handle, rigidly 95 fasten all parts together and prevent the handle from turning independently of the blade.

By making a screw driver with the shank passing entirely through the handle, there is 100 very little likelihood of the handle ever splitting, but as the same cannot turn independently of the blade, a better purchase can be obtained upon the work.

Of course, I do not wish to be limited to 105 the exact details of construction as here

shown, as these may be varied within the limits of the appended claim without departing from the spirit of my invention:

Having thus fully described my invention, what I claim as new and useful, is—

A tool comprising a handle having a frusto-conical extension at each end, ferrules each having a central bore diverging outwardly from a point intermediate its ends to 10 form a frusto-conical chamber, one of said ferrules being mounted on each end of the handle to inclose the frusto-conical extensions, projections formed with the ferrules and extending from the diverging portion of

the bore, said projections being embedded in 15 the handle extensions to prevent movement of the handle independent of the ferrules, a blade having a shank passing entirely through the handle and ferrules, a rivet passing through the inner ferrule and tool shank 20 beyond the inner end of the handle for securing said ferrule in place and a head formed on the outer end of the tool shank for fixing the outer ferrule to the tool shank.

In testimony whereof, I have hereunto 25 affixed my signature.

HENRY HOOD.

Copies of this patent may be obtained for five cents each, by addressing the "Commissioner of Patents, Washington, D. C."
